UNITED STATES PATENT OFFICE

JAMES C. HOBBS, OF PAINESVILLE, OHIO

FURNACE WALL

Application filed January 8, 1926. Serial No. 80,111.

My present invention relates to improvements in furnace walls and will be best understood from the following description and the annexed drawings, in which Fig. 1 is 5 a horizontal section through the wall, partly broken away, and Fig. 2 is a front elevation of the same.

In the illustrative embodiment, the furnace wall is built up of the usual refractory brick 10 or tile 8 having substantially parallel sides, in any of the usual manners, as, for instance, in horizontal courses, as illustrated. Preferably, there will be no bond between the courses, the friction between the courses being sufficient to hold the courses in place. At intervals along each horizontal course, at as many places as may be desired, the adjacent tile are spaced apart so as to leave an opening 9 between them with the portion of the 20 space 9 on the side of the wall away from the furnace bonded with mortar or cement 10, for, however, only a short distance in from the outer face of the tile. The exterior of the wall is covered with any suitable plastic insulating material 7, this plastic material being held between the casing plates 6 and the buckstays 5, the casing 6 being held against the buckstays in the usual manner.

When such a wall is used in a furnace, the 30 radiant heat which enters the spaces 9 is prevented from reaching the exterior face of the wall by reason of the presence of the bonding material 10. Moreover, these spaces are soon filled with an accumulation of light ash 35 which, while filling the spaces, will yield and therefore permit the motion of the tile tending to close the spaces. I may also apply a thin coating 11 of clay cement over the inner or furnace side of the tile 8 and across 40 the spaces 9 when the wall is first built. By "cement" I mean any plastic material which will adhere to the tile and by "clay" cement, I mean a clay which may be applied in plastic form and which will adhere to the tile 45 when applied. This thin coating 11 will be worn away after a short time by the abrasive action of the hot products of combustion in the furnace but not before the wall has been brought up to full furnace temperature.

50 In the usual furnace wall, much trouble

frequently arises with refractory materials that compose the walls, due to expansion and contraction. Such walls are usually continuous from end to end, so that small expansions and contractions, due to temperature changes, will cause destructive movements of the wall. Also higher temperatures on the inside of furnace side of such walls cause an arching which produces a tendency for the middle portion of the wall 60 to move inwardly toward the heat. By the arrangement which I have described, these difficulties are obviated, since it will be clear that the tile may expand laterally on its furnace side without causing the wall to buckle 65 because of the presence of the spaces 9. On the other hand, the outer faces of the tile are relatively cool and will therefore not expand materially and consequently the bonding material 10 may be used to hold the tile 70 fixedly in position in the wall. In other words, I have provided a wall of tile arranged so that each tile is held fixedly in position in the wall and yet the furnace side of the tile, which is subjected to the greatest expansion, 75 is free to expand without causing a buckling of the wall. At the same time, by the closure of the rear or outer ends of the spaces 9, no heat or gases can escape from the furnace.

I claim:

1. A furnace wall comprising a plurality of courses of refractory blocks, with at least one pair of tile in each course spaced apart, a bonding material in said space and only at one end thereof, whereby said pair of tile 85 is free to expand toward each other at one face but not at the opposite face of the wall, and a thin layer of clay cement over the other end of the space.

2. A furnace wall comprising a plurality of courses of refractory blocks, with at least one pair of tile in each course spaced apart, means sealing said space at the outer end thereof, and the space near the inner end thereof being covered with a thin layer of cement.

3. A furnace wall comprising a plurality of refractory blocks having substantially parallel sides and laid in courses, some of the adjacent tile of each course being spaced apart, means sealing said space at the outer end 100

thereof, and a thin layer of cement covering the inner end of the space.

4. A furnace wall comprising a plurality of horizontally disposed courses of tile having substantially parallel sides, certain tile in each course being spaced apart to form vertically extending spaces there-between, means securing the tile in position adjacent their outer portions and sealing said spaces, and a thin layer of cement over the inner ends of said spaces.

JAMES C. HOBBS.
